UNITED STATES PATENT OFFICE.

BRITTON E. BYRD, OF DURHAM, NORTH CAROLINA, ASSIGNOR TO MILL DEVICES COMPANY, OF DURHAM, NORTH CAROLINA, A CORPORATION OF NORTH CAROLINA.

KNOTTER DEVICE.

Application filed May 13, 1924. Serial No. 712,922.

To all whom it may concern:

Be it known that I, BRITTON E. BYRD, a citizen of the United States, and resident of Durham, in the county of Durham and State of North Carolina, have invented certain new and useful Improvements in Knotter Devices, of which the following is a specification.

This invention relates to a knot-tying 10 method and mechanism, and with respect to its more specific feature, to a method and mechanism for tying weaver's knots.

An object of the invention is to provide a simple, light-weight and easily operated 15 device of the character specified, capable of connecting two strands lying alongside of each other in spaced relation, by means of a weaver's knot.

In the usual construction of devices of 20 this character, the strands to be connected must be arranged in a certain predetermined manner, that is with the strands crossed on each side of the tying bill. The placing of the strands in this predetermined position 25 is an operation requiring time and care, and they must be so placed before the bill can form the knot.

A feature of the present invention is the 30 provision of means, operating in sequence with the bill, and controlled by the same operating mechanism, for moving a portion of one of the strands across the other strand, thereby to provide two points of crossing, spaced apart from each other and on opposite sides of the bill. That is, the strands are crossed ahead of the bill as it rotates in 35 the operation of forming the knot.

Another feature of the invention is the 40 provision of a stripper for straining the knot and for stripping it from the bill, operated in sequence with the bill and controlled by the same operating mechanism, and carrying a cutting blade for severing one strand, the other being cut by the bill, and 45 so arranged with respect to the direction of movement of the blade that the cutting edge will engage the strand with a shearing cut, said edge being adjustable.

In the drawings:

50 Fig. 1 is a side view of the improved knotter.

Fig. 2 is an end view looking from the left.

55 Fig. 3 is a side view with the near plate removed, showing the parts in one position.

Figs. 4 and 5 are similar views with the parts in other positions.

Fig. 6 is a plan view.

Figs. 7, 8, 9 and 10 are perspective views showing the different operations of the 60 knotter, and showing also the different positions of the strands during the formation of a knot.

Fig. 11 is a perspective view of the completed knot before it is tightened. 65

In the present embodiment of the invention a suitable frame is provided, composed of side plates 10 and 11, connected together in spaced relation by means of screws 12 and 13 and spacing mechanism to be described. 70 The screw 13 connects to the frame a handle member 14 which is adapted to be grasped in the palm of the hand, and a strap 15 connects the ends of the handle member, for engaging the back of the hand. 75

One of the spacing members is a substantially U-shaped bracket having arms 16 and 17, which extend between the plates 10 and 11, and the arms 16 have lugs 18 which engage slots in the plates 10 and 11, to hold 80 the bracket in place. A tying bill is supported by the arms of the bracket, and a spacing plate 19 which is arranged between the plates 10 and 11 opposite the bracket, the spacing plate being held in place by 85 lugs 20, which engage openings in the plates 10 and 11.

The tying bill comprises a shaft 21 journalled in the arm 17 of the bracket, and having between the arm 17 and the plate 19 a helical portion 22. The rear end of the shaft is pointed, as shown in Figs. 3 and 4, and engages within a recess in a screw 23, adjustably held in the plate 11 by means of the lock nut 24. The tying bill comprises a 90 clamping bill 25, a cutting bill spring 26 and an intermediate clamping and shearing jaw 27, the said jaw being pivoted between the bill and spring, on a pivot indicated at 28. The tying bill passes through a circular 95 opening in the arm 16 of the bracket, which is eccentric to the bill and the jaw 27 has a wing portion 29 in the opening, which by its engagement with the opening during the rotation of the bill operates the shearing 100 and clamping jaw.

Mechanism is provided at each side of the bill for supporting a pair of strands, that is the threads to be connected alongside each other in spaced relation. Each of the 110

plates 10 and 11 is offset outwardly at the end adjacent to the bill to form a thread guide and holding means, the said means being indicated generally at A and B, respectively. Referring to Fig. 1, it will be seen that the plate 10 is deeply notched in the offset portion to form a holder seat 30 for one strand, the bottom of the notch being rounded, and just above the bottom of the notch the holder has an upwardly extending lug 31^a, forming between it and the adjacent side wall of the notch a depression or seat 31 for the other strand. The plate 11 is also deeply notched at the offset portion, and the bottom of the notch is convex, as indicated in Figs. 7 to 10, forming on each side of the convexity a thread holding seat, 32 and 33, respectively.

A rocking member is pivoted to each of the plates 10 and 11, on the inner face of the offset portion 10, the members indicated at 34 and 35, and the member 35 is notched as shown at 36 to form a seat normally registering with the seat 33 of the plate 11. The member 34 has a notch 37 for engaging the strand seated in the adjacent seat 31, and the members 34 and 35 cooperate when they are rocked with other mechanism to be later described, to move that portion of the outermost strand between the plates 10 and 11 above the same portion of the inner strand, thereby to produce a crossing of the strands on each side of the tying bill.

The rocking members are controlled by the operation of the tying bill, and the said bill is operated by means of a lever 38, which is pivoted on the screw 13 before mentioned. The lower end of the lever forms a thumb piece adapted for engagement by the thumb of the user when the handle member is gripped in the left hand, and the upper end of the lever is forked, the arms of the fork engaging opposite sides of the helical portion of the tying bill, and rotating the bill when the lever is swung.

A cam shaft 39 is arranged between the plates at the upper edges thereof, and this shaft is provided at each end, outside of the plates 10 and 11, with radial arms 40 and 41, respectively. The lower ends of the respective arms are connected by links 42 and 43, with the adjacent rocking members, the links passing through slots in the connections between the offset portions of the plates and bodies thereof. The arrangement is such that when the shaft is oscillated, the radial arms being rigid therewith, the rocking members will be swung to move the strand held in the seats 36 and 37 inwardly above the strand held in the seats 30 and 32, thus to produce crossings of the strands ahead of the tying bill as it is rotated anti-clockwise.

Each of the links 42 and 43 is provided with a finger 42^a, and 43^a, respectively, which

in the normal position of the links are at the inner sides of the seats 30 and 32 and in position to engage the innermost strand during the longitudinal movement of the links to rock the members 34 and 35. Thus the fingers 42^a and 43^a cooperate with the rocking members in the crossing of the strands, and since the parts are so arranged that the fingers move past the rocking members as they are rocked, both strands are lightly clamped between the links and the rocking members, to properly tension the strands during the operation of the bill.

The shaft 39 is oscillated by means of the cam 44 secured to the shaft adjacent to the plate 10. The cam has a cam slot 45—46, the portion 46 being concentric with the screw 13, while the portion 45 is eccentric to the said screw. The adjacent arm of the fork of the lever 38 has a friction roller 37 which moves in the slot, and the slot is so shaped that at the beginning of the movement of the lever, the shaft 39 will be oscillated to rock the rocking members for enough to position the outer strand above and inside of the inner strand, after which the roller will ride in the portion 46 of the slot, without changing the position of the shaft 39. The other arm of the fork is also provided with a friction roller 48 which engages a cam arm 49 journalled on shaft 39, and the cam arm is so shaped that it will be unaffected by the movement of the lever 38 until the tying bill has been rotated through approximately 360°. Then the arm will be quickly swung to operate the shearing and stripping mechanism to be described.

The said mechanism is supported by an arm 50 extending forwardly from the shaft 39 and rigid with the cam plate 49, before mentioned. At its forward end the arm is bent sharply downward as shown in Figs. 3 and 4, to lie normally just in front of the arm 16 of the U-shaped bracket, at the right of the tying bill, and in a position such that the bill may rotate freely without interference from the said arm.

A cutting blade 51 is connected to the depending portion of the arm by a pivot 53 at the top of the blade, and a screw and slot connection 52 at the lower end of the blade. The slot extends transversely of the blade, and when the screw is loosened, the angle of the cutting edge of the blade to the direction of movement of the arm may be changed. The blade is so arranged that it engages the strand with a shearing cut.

The stripping mechanism is constituted by a U-shaped member or stirrup 54 having one arm secured to the face of the arm 50 remote from the blade, and the pivot 53 and screw and slot connection 52, above mentioned, are utilized to connect the stirrup to the arm 50. The stirrup is normally below

the tying bill with the body thereof lying transversely of the bill, and with the free arm of the stirrup on the opposite side of the bill from the blade. In the present instance the blade is at the right of the bill and the free arm of the stirrup is at the left. When the blade has completed the turning movement of 360° , the arm 50 swings upwardly, the blade shears the strand 10 s' at the right of the bill, and the free arm of the stirrup engages the same strand at the left of the bill, and strips the knot from the bill, acting at the same time to strain the knot.

15 A spring 55 is coiled about the screw 13 normally holding the lever 38 in the position of Figs. 1 and 3. One end of the spring is connected to the plate 11 and the other end is engaged with the lever.

20 In the operation of the improved knotter it is preferably held in the left hand with the handle member grasped by the fingers, and with the thumb on the thumb piece of the lever 38. The strands s and s^2 are laid 25 across the guides and holders A and B, with one strand, s^2 in the present instance, in the seats 30—32, and with the strand s' in the seats 31—33. The lever 38 is then swung by means of the thumb piece. Referring to 30 Figs. 3 to 5, inclusive, it will be noticed that the fork of the lever 38 may move for a certain distance from rest position without affecting a rotative movement of the tying bill. This movement is of sufficient extent 35 to permit the fork arm to operate the cam 44 to cause it to oscillate the shaft 39 before rotation of the bill commences. Through the arms 40—41 and the links 42—43, the 40 rocking members are rocked and that portion of the outer strand s' between the plates 10 and 11, is lifted above and moved to the inner side of the strand s^2 , thus crossing the strands on each side of the tying bill.

45 Further movement of the lever 38 will rotate the tying bill, and the bill will engage the crossed portions of the strands s' and s^2 in front of the bill, indicated at x' . This crossed portion x' of the strands, will be carried downwardly and toward the plate 50 10, the operation so far as described, forming in one strand, s^2 in the present instance, a loop through which the other strand passes. During this rotative movement of the bill, the clamping and shearing jaw 27 is operated to the open position of Fig. 4, and as the bill completes the movement of 180° , the inner strand s^2 engages between the jaw and the bill and is carried upwardly by the bill. Further movement of the bill causes 55 the jaw to be returned into position between the bill and the spring, clipping or shearing the strand s^2 , and simultaneously clamping the end thereof between the jaw and the clamping bill. At this time the bill is at the 60 end of its 360° movement.

The helical portion of the bill is so proportioned, that the final movement of the lever 38 does not affect the bill, this movement affecting solely the cam arm 49 and causing it to swing the arm 50. The first 70 movement of the arm upwardly brings the blade 51 into contact with the strand s^2 between the bill and the plate 10, and this end of the strand is severed. Continued movement of the arm causes the free arm of 75 the stirrup to engage the connected ends of the strands between the bill and the plate 11, and the knot is first stripped from the bill and afterwards strained to tighten it. The free arm of the stirrup, above mentioned, has a lug 56 to prevent disengagement of the strands from the stirrup.

80 The rocking movement of the rocking members not only positions that portion of the outer strand between the plates 10 and 11 at the inner side of the inner strand, but at the same time clamps the strands on each plate 10 and 11. The clamping action, however, is not sufficient to prevent movement of the strands with respect to the plates, being 85 merely sufficient to tension the strands as they are drawn past the guides and holders A and B, by the movement of the bill.

90 It will be evident from the description that the entire operation of connecting the strands by a weaver's knot is performed mechanically. The strands to be connected are merely laid across the notched end of the frame, and fall naturally into the seats provided for them. A movement of the thumb piece in one direction ties the knot, strains 95 it tight, and strips it from the bill and from the knotter. The rocking members cross the strands and in their movement of crossing, and after the crossing of the strands, exert 100 just enough tension on the strands to insure 105 the proper knotting. The three mechanisms which perform the three steps of the complete operation, that is the crossing of the strands, the formation of the knot, and the 110 stripping of the knotted strands, are controlled by the same operating mechanism, the lever 38, and operate in proper sequence.

115 The several steps in the formation of the knot are as shown in Figs. 7 to 10, inclusive. In Fig. 7 the strands are lying alongside each other. In Fig. 8 the outermost strand has been crossed above the lowermost strand, two points of crossing x' x^2 , being formed one at each side of the bill. In Fig. 9 the 120 strand s^2 has been looped about the strand s' , and the arms of the loop have been crossed, the said arms lying alongside the strand s' . In Fig. 10, one end of the strand s' is being looped about the strand s^2 , and the operation will be complete and the arms 125 of the loop will be crossed when the knot is withdrawn from the bill by the stripper. It will be noted from inspection of Figs. 9 and 10 that the knot is formed by looping one 130

strand about the other, with the arms of the loop crossed.

While the invention is shown in a preferred form, it will be apparent that changes and modifications may be made in the structure disclosed, without departing from the spirit of the invention as defined in the appended claims.

What I claim is:—

10. 1. In a device of the class described, means to form a weaver's knot from two strands to connect the same, including a tying bill, means to support the strands alongside each other in spaced relation on opposite sides of the bill, and means operated by the bill to cross the strands ahead of the bill, the said means including rocking members to support one strand, and mounted to swing with the strand across the other strand.
15. 2. In a device of the class described, the combination with a tying bill, of means to support a pair of strands alongside each other and at opposite sides of the bill, means to cross the strands ahead of the bill, said bill cutting one of the strands, and a common means to cut the other and to strip the strands from the bill.
20. 3. A device of the class described, comprising a tying bill, means to grasp and hold a pair of strands alongside each other in spaced relation and on opposite sides of the bill, means to cross the strands ahead of the bill and means for controlling the crossing of the strands in timed relation with the operation of the bill, the crossing means including rocking members having holders for the strands.
25. 4. In a device of the class described, the combination with a tying bill having cutting mechanism for one strand, a stripper, and a cutter for the other strand carried by the stripper.
30. 5. In a device of the class described, the combination with a tying bill having cutting mechanism for one strand, a stripper, and a cutter for the other strand carried by the stripper, and a common operating means for the bill and the stripper.
35. 6. In a device of the class described, the combination with a tying bill having cutting mechanism for one strand, a stripper mounted to move past the bill to strip the knotted strands therefrom, and a cutting blade on the stripper to cut the other strand.
40. 55. 7. In a device of the class described, the combination with a tying bill having cutting mechanism for one strand, a stripper mounted to move past the bill to strip the knotted strands therefrom, a cutting blade on the stripper to cut the other strand, and a common operating means for the bill and stripper.
45. 8. In a device of the class described, the combination with a tying bill having cutting mechanism for one strand, a stripper

mounted to move past the bill to strip the knotted strands therefrom, and a cutting blade on the stripper to cut the other strand, said blade engaging the strand with a shearing cut, and means to change the angle of the cutting edge of the blade.

9. In a device of the class described, the combination with a tying bill, of holders for supporting a pair of strands on opposite sides of the bill, said bill between the holders, and rocking members adjacent to the holders to engage a portion of one strand and move it across the other, thereby to provide points of crossing of the strands at opposite sides of the bill.

10. In a device of the class described, the combination with a tying bill, of holders for supporting a pair of strands on opposite sides of the bill, said bill between the holders, and rocking members adjacent to the holders to engage a portion of one strand and move it across the other, thereby to provide points of crossing of the strands at opposite sides of the bill, said members having means to tension the strands.

11. In a device of the class described, the combination with a tying bill, of holders for supporting a pair of strands on opposite sides of the bill, said bill between the holders, rocking members adjacent to the holders to engage a portion of one strand and move it across the other, thereby to provide points of crossing of the strands at opposite sides of the bill, said members having means to tension the strands, and a common operating means for the bill and the members.

12. In a device of the class described, the combination with a tying bill, of holders to support a pair of strands to be knotted alongside each other on opposite sides of the bill, and means to engage the portion of one strand between the holders and move it across the other strand, said means cooperating with the holders during and after the moving of the strand to tension both strands during the knotting operation.

13. In a device of the class described, the combination with a tying bill, of holders to support a pair of strands to be knotted alongside each other on opposite sides of the bill, and means to engage the portion of one strand between the holders and move it across the other strand, said means cooperating with the holders during and after the moving of the strand to tension both strands during the knotting operation, the moving means for the strand comprising rocking members mounted adjacent to the holders and operating in sequence with the tying bill.

14. In a device of the class described, the combination with a tying bill, of means to support a pair of strands on opposite sides of the bill, means to engage one strand at opposite sides of the bill and move the en-

gaged portion of the strand across the other strand, mechanism to strain the knot and strip it from the bill, and a common means for the strand moving means, the bill and

5 the stripping mechanism to operate them in sequence, the strand moving means comprising rocking members to engage the one strand and cooperating with the strand supporting means to tension the strands during

10 the knotting thereof.

15. In a device of the class described, the combination with a tying bill, of means to support a pair of strands on opposite sides of the bill, means to engage one strand at opposite sides of the bill and move the engaged portion of the strand across the other strand, mechanism to strain the knot and strip it from the bill, and a common

means for the strand moving means, the bill and the stripping mechanism to operate them 20 in sequence, the stripping mechanism comprising an arm mounted to move across the supported strands and having means to engage one of the strands, the tying bill having means to cut one of the strands at one side 25 of the bill, the stripping mechanism carrying means to cut the other strand at the same side of the bill, said stripping mechanism engaging the strands to strip the knot from the bill at the opposite side of the bill 30 from the cutting means.

Signed at Durham in the county of Durham and State of North Carolina this 10th day of May A. D. 1924.

BRITTON E. BYRD.
